FOUNTAIN PEN

John A. Shea, Jersey City, N. J.

Application November 6, 1948, Serial No. 58,678

2 Claims. (Cl. 120—42.05)

1

This invention relates to fountain pens and more particularly to the means of holding the cap to the pen body.

Heretofore, due to tolerances in the manufacture of the fountain pen parts, the cap would loosen from the body. An attempt was made to solve this difficulty of temporarily attaching the cap to the body, by forming the normally circular bore of the cap into an oval shape, and then by pressure converting the oval shape to a circular shape symmetrical to the outer circular shape of the pen body, or to a circular ring on the pen body. The objection to this proposal is that the cap with an oval shaped bore appears incomplete to the user, or makes the impression of a second. Other efforts have been made, without entirely satisfactory results.

This invention contemplates the solution of the problem and consists in the provision of a ring directly on the pen body having a bore to fit a cylindrical shoulder of a pen body which ring has an outer peripheral portion of a contour symmetrical to the inner bore of the ring, that is, the ring has a constant thickness. One axis of the bore of the ring is larger than the diameter of the cylindrical shoulder of the pen body, and the axis at right angles to that axis, is smaller than that diameter. The inner contour of the cap is circular, and concentric with the cylindrical shoulder, though radially spaced therefrom, and when the cap is applied to the outer contour of the ring, a tight fit is obtained, by the inner circular contour of the cap having a diameter slightly less than the greatest outer axis of the ring, that diameter being longer than the shortest outer diameter of the ring. Thereby, a slight warping of the cap end takes place when the cap is applied to the ring, but this is so small as not to be noticeable. An advantage results in that a spacing of the cap from the ring remains, for the passage of air, thus preventing a suction pull when the cap is being removed from the ring.

The invention will be further described hereinafter, an embodiment shown in the drawings, and the invention will be finally pointed out in the claims.

In the accompanying drawings:

Fig. 1 is a longitudinal section of the improved pen;

Fig. 2 is an enlarged, partial sectional view; and

Fig. 3 is a transverse section taken on line 3—3 of Fig. 1.

Similar characters of reference indicate cor-

2

responding parts throughout the various views.

Referring to the drawings, the fountain pen body 10 has a subcaliber cylindrical portion 11, provided with a screwthreaded portion 11a for engaging the casing 11b of the pen, which has a subcaliber stem for the end of the ink sack 12. A metallic ring 13 is placed on the cylindrical portion 11, the outer surface of which ring 13 is exposed in the use of the pen when the cap 20 is applied to the pen body along its tapering end, shown on the left hand of Fig. 1. When the parts are assembled as shown in Fig. 2, the end of the casing 11b abuts against the end of the ring 13. The ring 13 being disposed between the shoulder 16 and the casing 11b, is held against axial movement. The sack 12 and the screwthreaded part 11a of the cylindrical portion 11 is concealed by the pen casing 11b, as known.

The improvement consists in having the ring 13, which is preferably of U-shaped cross section as shown, so shaped as to be of the same radial thickness throughout, but instead of being circular, it has one axis larger than an axis at right angle thereto. The mean length of these axes is substantially equal to the outer diameter of the cylindrical portion 11. When the ring 13 is applied to portion 11, a snug fit is provided against the shoulder 16, and in having the inner peripheral portion 15 of an axis length smaller than the outer diameter of the portion 11, a tight fit is obtained, the larger axis at right angles to the shorter axis being reduced to the extent of the enlargement of the smaller axis, by the pressure exerted by the portion 11 against the bore of the ring 13. Thereby, the ring 13 is held permanently on the portion 11. The outer long axis 18 in relation to the outer short axis 19 of the outer contour 17 is in direct proportion to the inner diameter of the open end of the cap 20, so that due to the inherent resiliency of the material forming the open circular end of the cap, one inner diameter of the open end of the cap will be slightly extended, and an inner diameter of the open end of the cap at right angles to said first diameter will slightly contract.

In Fig. 3, one embodiment is shown in which the portion 11 is cylindrical, and shown as a circular peripheral contour, the smaller inner axis of the bore of the ring 13 provides a snug fit with the portion 11, and the larger inner axis of the bore 15 of the ring 13 at right angles to the smaller axis, is longer than the diameter of the portion 11, thus providing spaces as shown. When a cap with a circular bore is applied to the outer contour 17 of the ring 13, then a snug fit

along the axis 18 is obtained and spaces 21 are provided along the axis 19, the axis 19 being at right angles to the axis 18. In each case, the diameter of the circular contour corresponds to the mean axis of the inner or outer contour of the ring 13.

The invention is then the combination of a ring having a uniform thickness, with a bore to fasten it to a part of the pen body and with an outer peripheral contour to fasten a cap thereto. The ring has inner and outer elliptic contours, the mean axis of the outer contour of the ring corresponding to the inner diameter of the circular contour of the open end of the cap, and the mean axis of the inner contour of the ring corresponding to the diameter of the cylindrical portion 11 of the pen body. Thus, when the cap is applied, a secure hold is obtained, since on the application of the cap the axis 18 may yield slightly in view of the space between the inner contour 15 and the portion 11. Also, ventilation spaces 21 between the outer contour of the ring and the bore of the cap are provided, which permit the ready removal of the cap.

The rings 13 are conveniently made by manufacturing circular rings of the same thickness throughout, that is, of concentric inner and outer contour, and then subjecting such circular rings to a slight pressure along any diameter, whereby the circular bore and external contour is slightly flattened.

I do not desire to be limited to the exact details of construction shown and described, for obvious modifications will occur to a person skilled in the art.

I claim:

1. In a fountain pen, the combination of a fountain pen body having an outer part, an interior sub-caliber cylindrical portion with a shoulder adjacent said outer part and a screw-threaded portion extending beyond said sub-caliber portion, a casing having interior threads

for engaging said screw threads, and having an end, and a metallic ring of uniform radial thickness throughout its circumference, seated in a groove formed by said subcaliber portion, said adjacent end of the casing, and said shoulder, said ring having a radially inner and outer concentric elliptical contour, the mean radius of the largest and smallest diameters of the outer contour of the ring being substantially equal to the inner diameter of the circular open end of the bore of a cap for the fountain pen, and the radius of the smallest diameter of the inner contour of the ring being slightly less than the outer diameter of the subcaliber cylindrical portion of the pen body, whereby the pressure of the cap on the outer contour of the ring is translated yielding through the ring to the subcaliber cylindrical portion of the pen body.

2. A fountain pen comprising a pen body having means defining a shoulder and a threaded, reduced portion extending beyond said shoulder, a pen casing section threaded onto said reduced portion and having a shoulder facing said first-named shoulder, and a resilient, metallic, generally circular but out-of-round clutch ring telescoped over said pen body and positioned between said facing shoulders and having at least portions projecting laterally beyond the adjacent peripheral surfaces of said pen body and casing section.
